UNITED STATES PATENT OFFICE

ARTHUR I. RISER, OF CHICAGO, ILLINOIS, ASSIGNOR TO U. S. BOTTLES MACHINERY COMPANY, OF CHICAGO, ILLINOIS, A CORPORATION OF ILLINOIS

CAPPING APPLIANCE

Application filed April 25, 1928. Serial No. 272,635.

My invention concerns mechanisms or machines for applying screw-threaded caps to similarly threaded bottles, jars or the like, automatically, and an object of the invention is to supply an apparatus of this type which will operate efficiently, which will discharge any of the caps for which the bottle or jar or its equivalent is not provided, and which is comparatively simple in structure and relatively inexpensive to manufacture.

To permit those trained in this industry to fully understand the invention, I have shown a preferred embodiment of the same in the accompanying drawings forming a part of this specification, and in which like reference characters have been employed throughout the several views to designate the same parts of the structure.

In these drawings,—

20 Fig. 1 is a substantially central, vertical section through the appliance on line 1—1 of Figure 2;

Fig. 2 is a horizontal section on line 2—2 of Fig. 1;

25 Fig. 3 is a diagrammatic or developed view of the cam portion of the machine and the capping-heads associated therewith;

Figs. 4, 5 and 6 illustrate a portion of the mechanism in its different positions during 30 the capping operation; and

Fig. 7 is a horizontal section on line 7—7 of Fig. 4, the parts being viewed in the direction indicated by the arrows.

Turning to these drawings, it will be observed that the appliance includes an upright, revolute shaft 10 and its aligned, stationary extension 11, the former being rotatable in its bearing 12 and the latter supported by its bearing 13, the upper, reduced-diameter end of shaft 10 being accommodated in a suitable socket in the lower end of shaft 11.

Shaft 10 is revolved by a drive-shaft 14 through bevel-gears 15 and 16, such shaft having fixed thereto a round support 17 provided with a plurality (eight in the present

instance) of semicircular recesses or pockets 18, 18, each adapted to accommodate a bottle or the like 19 having a screw-threaded neck 21 designed to receive a correspondingly threaded cap 34.

A shorter, vertical shaft 22 is supported inside of a sleeve 33 by a bearing 23, the shaft being rotated from the drive-shaft 14, in correct timed relation to the other parts of the mechanism, by a pair of sprocket-wheels 24, 24, their associated sprocket-chain 25, a second shaft 26 on which one of the sprocket-wheels is mounted, and coaxing bevel-gears 27 and 28.

At its top end, the constantly-revolving shaft 22 has eight, radiating or outstanding arms 29, 29 having suitable, curved ends 31 adapted to slide the caps 34 individually in a curved path over the top of a stationary table or ledge 32 mounted on the upper end of the sleeve 33, the caps being delivered to the top surface of such table, shelf or support, one at a time, right side up, from a chute 35 associated with a suitable source of cap supply, the ends of the arms sweeping the caps along ahead of them until they are removed from the table by other parts of the machine hereinafter described.

The vertical, constantly-rotating shaft 10 has a spider 39 pinned thereon, and consequently rotatable therewith, such spider having eight pairs of registering, upright bearings 40, 41, each accommodating a rotating, slidable shaft 42 fitted with and slidable through a pinion 43 located between the spider 39 proper and an upper member or portion thereof 45 which is provided with the bearing 41.

It is, of course, understood that each pinion 43 has a driving relation with its shaft 42, as by a slot and keyway, the shaft, however, being capable of reciprocation through the pinion.

The eight pinions 43 mesh with a suitably-supported, stationary, large gear 44, so that

as the pinions travel around the axis of such gear they are revolved about their own axes.

Each shaft 42 and its hollow extension-shaft 54, the two being screwed together, are supplied with a bearing member 46, mounted 5 on the lower end of a slide 47, arranged to reciprocate on the spider and equipped with an operating roller 48 positioned and arranged to travel between a pair of stationary cam-bars 49, 51 mounted on a plurality of 10 supports 52 depending from a spider 53 adjustably supported, by suitable mechanism not necessary to describe, on the shaft 11.

Shaft 54, at its lower end, carries, or has 15 integral therewith, a head or disc 55 forming one element of a suitable friction-clutch having a friction-disc 56 between the under face of the part 55 and the top, flat surface of a skeleton member 57 carrying a capping-head 58.

To hold such head and its associated parts down to their work, a coiled spring 59 encircles the shaft 54 and presses at its upper end against a collar 61 keyed to and rotatable 25 with the shaft 54, and located just below the bearing 46, the spring bearing at its lower end against the hub of the head 55, the descent of the related, vertically-movable parts being limited by a collar 62 on the shaft 42, 30 and designed, when the shafts have reached their lowermost limit, to engage a ball-bearing 63 resting on the top of the element 46, it being understood that the shaft 54 is slidable in each of the members 61 and 63.

35 The lower opening 64 of the capping-head 58 has a ring 65 fixed therein and provided with a central, flaring mouth with a roughened or corrugated surface, whereby it may firmly and securely grasp the cap and turn it during its application to the bottle-neck.

40 Internally, each head 58 slidably accommodates a tube 66 having a lower, flaring mouth, as shown in Fig. 4, and normally held pressed down by a coiled spring 67 interposed between the upper end of the tube and a centrally-apertured disc 68 in the lower end of the hollow shaft 54, the downward movement of the tubular member being limited by an external enlargement 69 thereon designed 45 to contact with the top surface of the ring 65, as shown in Fig. 5.

The lower portion of the chamber within the hollow shaft 54 is connected, through a passage 71 and a hose 72, with a port or cavity 55 73 in the upper surface of the collar 61, and which is in constant communication, during the rotation of the shaft 54, with an annular channel 74 in the under surface of the stationary element 46.

60 Each groove 74, by means of a passage 75 and an individual hose 76, is connected to a corresponding aperture 77 extended through the spider or support 39, so that during a portion of the rotation of the element 39 it 65 will be in operative association with a groove

78 in the bottom of a stationary disc 79 positioned just below the gear 44, such arcuate or curved channel 78 extending only part way around the axis of the shafts 10 and 11, as is depicted in Fig. 2.

Such groove or channel 78 is constantly subjected to a suitable degree of suction by means of a hose 81 connected to such a source of suction and joined to a passage 82 extended through the parts 79 and 44.

The operation of the mechanism takes place 75 practically as follows:

Assuming that, by hand, or by suitable, automatic feeding means, the uncapped, screw-threaded bottles are delivered into the compartments 18 of the support 17 and are revolved thereby around the axis of the shaft 10 at a uniform, uninterrupted speed, and that shaft 22 and its arms 29 are feeding the screw-threaded caps 34 on the table or shelf 32 in the manner already stated, and that the spider or support 39 is also constantly revolving, maintaining the capping-heads 58 in register with the bottles beneath them, such heads rotating continuously about their own axes, when any particular cap, during its sliding or sweeping travel on the support 32, comes into alignment or register with the corresponding bottle, which passes beneath the cap table, as shown in Fig. 1, the suction will have been applied, through the stated connections, to the corresponding tube 66, and the correlated capping-head will have been caused to descend by the cam-bars to fit over the cap, as shown in Fig. 4, the sliding tube 66 being pushed up against the action of its spring 67, but assuring an efficient engagement of its lower end with the cap.

As the capping-head, during its unvarying rotation about the axis of shaft 10, sweeps such cap from its support 32, the cap will be held suspended just below the head by the action of the suction in tube 66 in the relation indicated in Fig. 5, the descent of the tube and cap, of course, being limited or restricted by the engagement of the circular rib 69 with the top face of the ring 65.

Shortly thereafter, the revolving capping-head and its cap move down and screw the cap on to the neck of the bottle beneath, the spring being somewhat compressed, as shown in Fig. 6, and the tube 66 receding into the head, whereby the cap is at first lightly applied to the neck, and then is forcibly revolved by the ring 65, which screws it firmly on the neck.

As soon as the cap is fully screwed home on such neck so that it cannot turn any more, sufficient resistance to such turning action will have been created to cause the friction-clutch 55, 56, 57 to slip, thus avoiding an excessive turning action on the cap.

The parts continue their steady rotation about the axis of the shaft 10, the capping-head rises, and when the port or passage 77 130

passes beyond the end of the suction channel 78 the suction terminates, so that if, for any reason, any of the pockets 18 does not receive its bottle, the correlated cap will be held by 5 the suction in the capping-head until the suction ends, whereupon, the cap being no longer held or supported by the suction, will drop out of the capping-head, so that the latter will be ready to receive another cap at the 10 proper moment.

Of course, there are several bottles undergoing simultaneously different phases of the capping operation, whereby the machine not only performs its work efficiently, but it also 15 has relatively high capacity.

The invention, as those skilled in this art will understand, and as defined by the appended claims, is not limited and restricted to the exact details of structure shown and 20 described, and many more or less radical changes may be incorporated in the mechanism without departure from the heart and essence of the invention and without the loss of any of its substantial benefits.

25 I claim:

1. In a capping-appliance, the combination of a stationary table, a revolute support adapted to receive screw-threaded containers, a capping-head on said support above, in 30 register with, and slidable toward and from each such container on the support, means to revolve said support to carry said containers in sequence beneath, and the corresponding capping-heads above, said table, 35 means to rotate said capping-heads about their own axes, means to slide said capping-heads toward and from their containers, means to feed screw-threaded caps on said table individually into register with said 40 capping-heads as the latter pass over said table, means recedably mounted in said capping-heads and adapted to be subjected to suction to retain the caps therein during their travel after leaving the table until they 45 descend to their containers, means to control the suction exerted by said recedable means to release any cap from its head for which no corresponding container is present to permit such head to receive another cap from the 50 table, and means in each capping-head to grasp its cap sufficiently firmly to screw it on to the corresponding container, the corresponding recedable means automatically retreating into the capping-head during such 55 cap-screwing operation.

2. In a capping-appliance, the combination of a stationary table, a revolute support adapted to receive screw-threaded containers, a capping-head on said support above, in 60 register with, and slidable toward and from each container on the support, means to revolve said support to carry said containers in sequence beneath, and the corresponding capping-heads above, said table, means to rotate 65 said capping-heads about their own axes,

means to slide said capping-heads toward and from their containers, means to feed screw-threaded caps on said table individually into register with said capping-heads as the latter pass over said table, an open-ended tube slidable in each of said capping-heads, means to apply suction intermittently to said tubes to retain the caps in said heads during their travel after leaving the table until they descend to their containers and to release any 75 cap from its head for which no corresponding container is present to permit such head to receive another cap from the table, and means in each capping-head to grasp its cap sufficiently firmly to screw it on to the corresponding container, the corresponding slidable tube automatically receding into the capping-head during such cap-screwing operation.

3. In a capping-appliance, the combination of a stationary table, a revolute support adapted to receive screw-threaded containers, a capping-head on said support above, in register with, and slidable toward and from each such container on the support, means to revolve said support constantly to carry said containers in sequence beneath, and the corresponding capping-heads above, said table, means to rotate said capping-heads constantly 90 about their own axes, means to slide said capping-heads toward and from their containers, means to feed screw-threaded caps on said table individually into register with said capping-heads as the latter pass over said table, an open-ended, downwardly spring-pressed tube slidable in each of said capping-heads, means to apply suction intermittently to said tubes to retain the caps in said heads during their travel after leaving the table until they descend to their containers and to release any 95 cap from its head for which no corresponding container is present to permit such head to receive another cap from the table, and means in each capping-head to grasp its cap sufficiently firmly to screw it on to the corresponding container, the corresponding slidable tube automatically receding into the capping-head during such cap-screwing operation.

4. In a capping-appliance, the combination of a revolute support adapted to receive screw-threaded containers, a capping-head on said support above, in register with, and slidable toward and from each container on the support, means to revolve said support to carry said containers in sequence beneath, and the corresponding capping-heads above, said table, means to rotate said capping-heads about their own axes, means to slide said capping-heads toward and from their containers, means to feed screw-threaded caps individually into register with said capping-heads, means recedably mounted in said capping-heads and adapted to be subjected to suction 120 to retain the caps in said heads during a portion of the cap-screwing operation.

tion of their travel, means to control the suction exerted by said recedable means to release any cap from its head for which no corresponding container is present to permit such head to receive another cap, and means
5 in each capping-head to grasp its cap sufficiently firmly to screw it on to the corresponding container, the corresponding recedable means automatically retreating into the capping-head during such cap-screwing operation.

In witness whereof I have hereunto set my hand.

ARTHUR I. RISER.
